(57) **CLAIM**

The ornamental design for a folding seat for mobility as shown and described.

DESCRIPTION

FIG. 1 is a front perspective view of a folding seat for mobility showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a perspective view thereof showing the design in use.
